UNITED STATES PATENT OFFICE.

WILLARD E. DOW, OF BRAINTREE, MASSACHUSETTS.

IGNITION SYSTEM FOR GAS-ENGINES.

1,030,288.

Specification of Letters Patent. Patented June 25, 1912.

Application filed September 18, 1907. Serial No. 392,797.

To all whom it may concern:

Be it known that I, WILLARD E. Dow, a citizen of the United States, and resident of Braintree, in the county of Norfolk and State of Massachusetts, have invented an Improvement in Ignition Systems for Gas-Engines, of which the following description, in connection with the accompanying drawings, is a specification, like letters on the drawings representing like parts.

My invention is a special ignition system for permitting the operation of a gas engine in connection with a battery and spark coil or in connection with a magneto at will without stopping the engine. In other words, by my invention the operator can start the engine by actuating the spark plug or plugs at the start in connection with the induction coil and battery circuit, and then, after the engine is started, he can, by a simple rotation of the same starting switch, cut out the coil and its battery circuit and cut in a magneto circuit, continuing the running of the engine thereafter in connection with the magneto. This greatly simplifies the usual mechanism, saves battery consumption, and renders special skill less necessary.

While my invention is specially intended for use with automobiles, it is not confined thereto.

In the drawings, in which I have illustrated a preferred embodiment of the invention, Figure 1 shows the same in top plan, and Fig. 2 in longitudinal section; Fig. 3 is an end view of the operating handle and switch plate, which is the only part visible externally of the machine; Fig. 4 is an end view of the inner end of the switch opposite the handle; Fig. 5 is a cross-sectional view on the line 5--5, Fig. 2; Fig. 6 is a cross-sectional view on the line 6--6, Fig. 1; Fig. 7 is a diagrammatic view illustrating the connections; and Fig. 8 is a diagrammatic view showing another use of the invention.

The constructional details of the switch itself are exceedingly simple, and its simplicity and compactness are among the important advantages of my invention. In a barrel or insulating tube 1 is mounted an insulating rotary member 2, said barrel or cylinder being provided with stationary contact posts, herein shown as arranged in three series 3, 4, 5, each series, as herein shown, comprising four posts set in accurate longitudinal alignment radially in the cylinder,

and extending through the same to co-operate with two series of contacts 6, 7 in the rotary member 2, arranged at right angles to each other, as shown best in Fig. 6. In order that these contacts 6, 7 shall always make close, perfect contact with the stationary posts, I have provided them with carbon plugs 8 held outwardly by a spring or springs 9 in tubes 10 and 11. The carbon plugs are exceedingly durable, and the construction shown also has the merit of being simple and inexpensive to make and put together. The posts are herein shown as provided with a usual groove 12 and also a thumb nut 13, so as to accommodate the switch to different kinds of terminal clips. At its front end the rotary member 2 is provided with a projecting axle 14 held immovably in the rotary member by a pin 15, and provided at its outer end with a handle 16. The handle swings over a face-plate 17 into the three positions 18, 19, 20, being limited in its extreme throw by posts 21, 22, a spring held plunger 23 tending to hold the handle in whichever of the three positions it may occupy. At its opposite end the switch has three stationary posts 24, 25, 26, corresponding to the three positions of the handle, said posts being mounted in an insulating block or cap 27 secured in position by any suitable means, as by the post 25 and a screw 28 which screw endwise into the barrel or cylinder 1. On the adjacent end of the rotary member 2 is fast a contact plate 29 having a narrow end 30 and a wide sector-shaped end 31, and provided centrally with a post-like projection 32 which extends through and bears in constant engagement with a contact plate or strap 33 extending from the stationary post 25. At its free end the projection 32 carries a pointer 34, beneath which is also preferably provided a nut 35 for pressing down on the contact plate or strap 33 for maintaining good contact at all times.

The posts 24 and 26 are internally hollow and provided with spring pressed beveled plungers 36 for maintaining perfect contact with the contact plate 29, being beveled to enable them to ride up on the plate conveniently when the rotary member is turned.

In Fig. 7 I have shown diagrammatically the wiring for my apparatus, the contact 3 connecting with the secondary 37 of an induction coil, whose primary 38 connects with a battery 39 at one end and an inter-

rupter 40 at the other end on the engine 41. The contact 4 connects by a wire 42 with a spark plug 43 for operating a cylinder of the engine in usual manner. The contact 5 connects by a wire 44 with the secondary winding of the armature of the high tension magneto 45. The contact 24 connects by a wire 46 with the battery 39, the contact 25 by a wire 47 with any suitable ground, as 10 on the engine, and the contact 26 connects to the wire 48 of the primary winding of the armature of the high tension magneto 45. Thus, by rotating the handle 16 to the right into the position shown in the drawings, the spark plugs will be operated in connection with the induction coil and battery circuit, at which time the magneto remains inoperative, so that no damage can 15 be done because of its necessary continuous rotation. After the engine has been started properly through the energizing of the spark plugs 43 by the induction coils, the operator turns the handle to the extreme left to position 20, Fig. 3, thereby cutting 20 out the battery and simultaneously connecting the contacts 4 and 5, the result being that the charge continues to be properly exploded by the energizing of the spark plugs from the magneto. At the same time 25 the circuit to the coil is opened, rendering the coil inoperative by the breaking of the circuit between contacts 3 and 4. In other words, I cut in the coil and cut out the magneto by one movement of the switch, and by 30 a reverse movement of the switch I cut in the magneto and cut out the coil. When the switch is moved to the middle point 19, Fig. 3, both the magneto and coil are cut out, as the contact end 30 is thrown out of contact 35 with the contact 24 but the sector end 31 continues the ground circuit 48, 26, 31, 25, 40 47 of the magneto, so that the latter is rendered inoperative.

It will be understood that I have omitted 45 various usual details as to the timing of the circuit, etc., as my invention does not reside in the particular arrangement of engine or circuit closer or magneto or coil, but in the arrangement of means for cutting in to the spark plug circuit the coil and cutting out the magneto, and vice versa, the specific means or switch whereby this is 50 accomplished being also new and also herein claimed.

It will be understood that I have not attempted in the diagram, Fig. 7, to show all 55 the winding for a multi-cylinder engine. For the latter the current from the magneto will usually be distributed to the different 60 posts 5 by a suitable distributer, and the same may take place in connection with the induction coil; although preferably a separate coil is used for each spark plug. By my construction of switch, it will readily be 65 seen that any number of spark plugs may

readily be accommodated, inasmuch as the switch may be made as long or short as desired, with as many contacts in each series as may be necessary. Also, it is equally satisfactory when operated with a single coil and a single magneto, as illustrated in Fig. 8, in which a wire 49 is shown leading to a distributer 50 for operating successively any number of spark contacts 51 from either the magneto 45 or the induction apparatus 70 52.

The switch *per se* is not herein claimed, being duly claimed in a divisional application, Serial No. 574,465.

Having described my invention, what I claim as new, and desire to secure by Letters Patent, is:

1. The herein described ignition system, comprising an induction coil contact, a magneto contact, a spark plug contact, a battery contact, and a ground contact, combined with means including circuit connections and an induction coil, a magneto, a spark plug, and a battery, operating in one position to close connection between said coil contact and spark plug contact, and between said battery contact and said ground contact, and in another position to break both of the aforesaid connections and make connection between said spark plug contact and magneto contact. 90

2. The herein described ignition system, comprising a spark plug contact, a magneto circuit, two magneto contacts for said magneto circuit, an induction coil, two induction coil contacts for the secondary and primary circuits thereof, a ground contact, and means including circuit connections and said induction coil, a magneto, and a spark plug co-operating with the aforesaid contacts, when in one position, to close connection between coil contact and the spark plug contact, and, when in another position, to close connection between said spark plug contact and the magneto circuit, said means, in passing from its first mentioned position to the other position, cutting off all circuit connection from the spark plug contact. 100

3. The herein described ignition system, comprising a spark plug contact, a magneto circuit, two magneto contacts for said magneto circuit, an induction coil, two induction coil contacts for the secondary and primary circuits thereof, a ground contact, and means including circuit connections and said induction coil, a magneto, and a spark plug co-operating with the aforesaid contacts, when in one position, to close connection between a coil contact and the spark plug contact, and, when in another position, to close connection between said spark plug contact and the magneto circuit, said means, in passing from its first mentioned position to the other position, breaking the first mentioned closed circuit and closing connection between said 110 115 120 125 130

ground contact and the magneto circuit until after said breaking of said first mentioned closed circuit.

4. The herein described ignition system, comprising a spark plug contact, a magneto circuit, two magneto contacts for said magneto circuit, a ground contact to operate in connection with one of said magneto contacts, an induction coil, two induction coil contacts for the secondary and primary circuits of an induction coil, and means including circuit connections and said induction coil, a magneto, and a spark plug coöperating with the aforesaid contacts, when in one position, to cut a coil contact into efficient operative relation with the spark plug contact, and to close connection between said ground contact and one magneto contact, and, in moving from said position to another position, to sever the aforesaid relation between the spark plug contact and said coil contact, break said connection between the ground contact and adjacent magneto contact and make connection between the other magneto contact and the spark plug contact.

5. The herein described ignition system, comprising a spark plug contact, a magneto having two circuits; two magneto contacts for the two circuits of said magneto, an induction coil, two induction coil contacts for the secondary and primary circuits thereof, a ground contact, and means including circuit connections and said induction coil, said magneto, and a spark plug coöperating with the aforesaid contacts for cutting the coil contacts into efficient closed circuit position with relation to the spark plug contact and simultaneously putting the magneto contacts in inoperative relation thereto, and vice versa.

6. The herein described ignition system, comprising a spark plug contact, a magneto having two circuits, two magneto contacts for the two circuits of said magneto, an induction coil, two induction coil contacts for the secondary and primary circuits thereof, a ground contact, all of said contacts being stationary, and a movable member provided with coöperating movable contacts arranged to cut the coil contacts into efficient circuit relation to operate the spark plug and to render, at the same time, the magneto inoperative, and when moved to another position, to render the coil inoperative with relation to the spark plug and to render the magneto contacts and circuits efficient with relation to the spark plug combined with said spark plug, magneto and induction coil and their circuits.

7. In an ignition apparatus for a multi-cylinder engine, a spark plug for each cylinder, a battery, a magneto having a secondary coil, a common switch, induction coil mechanism having secondary connections with and operable by said common switch and having a primary sparking circuit including said battery and said common switch, wires from said common switch having electrical connection with the magneto secondary, electrical connection from said common switch to the several spark plugs, and a primary magneto circuit including said common switch.

8. In an ignition apparatus for a multi-cylinder engine, a single spark plug for each cylinder, a battery, a magneto and its secondary winding, induction coil mechanism, a common switch having provision for transmitting current from the secondary portion of said induction coil mechanism for the several sparking plugs and provision for transmitting current from the magneto secondary winding to the several spark plugs, a primary circuit for said induction coil mechanism including said battery and said common switch, and a primary magneto circuit including said common switch.

9. In an ignition apparatus for a multi-cylinder engine, a single spark plug for each cylinder, a battery, a magneto, a common switch having a multiplicity of fixed contacts and a multiplicity of movable contacts, spark coil mechanism, and means for delivering induced current therefrom to fixed contacts of said switch, means to deliver current from the magneto secondary to other fixed contacts of said common switch, connections from still other fixed contacts of said common switch to the several spark plugs, a primary sparking circuit including said battery and said common switch, and a primary magneto circuit including said common switch, the fixed and movable contacts of said common switch being so related that, in one position, they close the secondary magneto circuits to said spark plugs and break the primary magneto circuit and the primary and secondary spark coil circuits, and in another position close the primary and secondary spark coil circuits and the primary magneto circuit and break the secondary magneto circuits.

In testimony whereof, I have signed my name to this specification, in the presence of two subscribing witnesses.
